HEAT EXCHANGER

Erik Torvald Linderöth, Sundsvall, and Curt Fredrik Rosenblad, Stockholm, Sweden; said Linderöth assignor to said Rosenblad

Application October 17, 1932, Serial No. 638,220,
and in Sweden July 26, 1930

12 Claims. (Cl. 257—245)

This invention refers to heat-exchangers, and more particularly to heat-exchangers having heat transmitting surfaces of sheet metal bent to a spiral shape. Heat-exchangers of said latter type are very advantageous in respect of their heat economy but have had heretofore no practical use because the apparatus could not fulfil the requirements necessary for practical operation, viz:

1. The apparatus should be able to resist high pressures from the liquids, between which the transmission of heat is effected, without any deformation of the spiral plates and without any change of the distance between said plates, because otherwise the resistance to the flow would be considerably increased and consequently one of the most important advantages of such apparatus be lost. Moreover, the apparatus should be able to resist all stresses and strains to which it is exposed when transported.
2. The inlets and the outlets of the spiral channels, in which the liquids flow, must be formed in such manner that the flow of the liquids is not throttled or impeded.
3. All heat transmitting surfaces should be easily accessible on both sides for cleaning.

The chief object of this invention is to create a heat-exchanger of the type referred to and fit for resisting all strains and stresses met in normal operation. The apparatus shall also have such compactness and stability as to withstand transportation without damage.

A further object of this invention is to reduce the losses of energy to a minimum.

Other objects will be evident from the following specification and claims.

Some embodiments of the invention are shown in the annexed drawing.

Fig. 1 shows a vertical section through the apparatus on the line I—I in Fig. 2. Fig. 2 is a vertical section on the line II—II in Fig. 1. Fig. 3 shows a section on the broken line III—III in Fig. 2, on a somewhat larger scale. Fig. 4 is a horizontal section of a detail on a larger scale, to illustrate the sealing device at the edges of the spirals. Fig. 5 shows, partly in section, a perspective view of the rubber packing shown in Fig. 4. Figs. 6 and 7 are sections of details, illustrating modifications of the sealing device shown in Fig. 4. Fig. 8 is a partial section through one of the connecting pipes at the periphery and shows a modification of the device for stabilizing the same.

Referring now to the drawing, 1 and 2 indicate two rectangular plates, or sheets of metal, which are bent to parallel spirals, thus forming

between themselves two spiral channels 3, 4, each receiving one of the liquids, between which the transmission of heat is to be made. Each plate 1, 2 then forms a heat transmitting surface, in contact with the hot liquid on one side and with the cold liquid on the other side.

Around the plates two rings 5 are secured to give the apparatus an increased stability and on said rings supports or feet 6 are secured on which the apparatus rests. In said rings holes 7 for bolts 29 are bored to enable said plate 8 to be secured to the apparatus.

To the top of the apparatus two flanged tubes or connection pipes 9, 10 are secured which are cut axially to a distance substantially corresponding to the whole axial width of the plates 1, 2, as indicated at 11 and said plates are secured to the tubes 9, 10 on both sides of said cuts or slots 11 in such manner that the channels 3 or 4 communicate with said tubes 9, 10. In the radial direction the slots or cuts 11 have a greater width than the ordinary radial width of the channels 3 or 4, and said channels are, as indicated at 12 in Figs. 1 and 3, successively widened for a distance adjacent to the tubes 9, 10 in the direction towards the slots 11 in such manner that the cross-sectional area of each channel successively increases in the direction to the tubes 9, 10 for a certain distance or decreases in the opposite direction.

In the centre of the apparatus the innermost winding of the spiral is provided with two smaller side plates 13 to form a cylindrical chamber 14. Said chamber encloses a central tube or connection pipe 15, closed at one end by one of the side plates 13 and at the other end by a special end closure plate 16, the chamber formed within the tube 15 being thus entirely sealed from the chamber 14. In one of the side plates 13 a pipe 17 is mounted, communicating with the chamber 15 and in the other of said side plates 13 another connecting pipe 18 directly communicates with the chamber 14.

The tube 15 is cut or slotted axially at 19 substantially throughout its whole length and liquid-tightly connected with the channel 3 at said slot. Similarly, the channel 4 discharges into the chamber 14 substantially throughout the whole axial width thereof at 20. Just as the other ends of the channels at 11 the ends of the channels at 19 and 20 have, for a certain length, a radial width successively increasing in direction to 19 and 20.

Because the inlet and the outlet openings at 11 and 19 extend substantially across the entire axial

width of the spirals so as to prevent any throttling of the currents of the liquids at the inlets and the outlets, it is very difficult to obtain a sufficient resistance or strength at said places inasmuch as 5 the tensile stresses in the outermost winding of the spiral plates are transformed to bending stresses in the inlet and outlet tubes 9, 10 and, similarly, bending stresses are originated in the tube 15, if the pressure in one of the two channels 10 nels 3, 4 is higher than that in the other. To absorb such stresses without any use of material of extreme thickness a number of stays or tie-rods 21 are secured, for instance, riveted or welded, across the openings 11 and 19. Said stays 15 have a narrow width in the direction at right angles to the direction of flow.

It was already mentioned that it is very important in heat-exchangers of this type that the plates 1 and 2 be on their total surface prevented 20 from displacement in relation to each other and from local outward or inward bulging, buckling or the like because otherwise the spiral channels will be throttled. For this reason distance pieces 25 are secured, preferably, welded, between the plates 1, 2 adjacent to the edges of the spirals. Because the plates as a result of their curved shape have a high resistance to stresses and pressure and in addition are always kept in the correct position to each other by the distance pieces, 30 the apparatus has a high stability and resistance to stresses and pressure.

A number of stays 23 are provided between the tubes 9, 10 to stabilize them further and absorb the couple of forces acting on said tubes. Thus, 35 the plates and also the tubes 9, 10 are further secured against displacement so that the widened parts of the channels 3 or 4 at 12 cannot be diminished and thus the resistances to the flow cannot be increased.

40 To effect the sealing rendered necessary by the open construction of the channels 3 or 4 at the end surfaces of the apparatus sealing strips or packings 24 of rubber, leather or other suitable material are inserted between the plates 1, 2 at said ends. In the embodiment shown, said packings consist of sealing strips having a V-, or U-, or U-shaped cross section with the bottom or base turned towards the adjacent side plate 8, so that the pressure above atmospheric in the 45 channels 3 or 4 presses the packings outwards against the side plate 8 and also against the plates 1, 2. For cleaning the apparatus the strips 24 may easily be removed, because they are loosely inserted between the plates. Preferably, the legs 50 or flanges 24a of the packing should, as shown in Fig. 5, have a greater distance from each other in their free and unstrained state before they are inserted between the plates than they have after such insertion so as to cause the packing to engage the plates with a certain initial pressure.

The bottom or base of the packing should also at all places be secured in such manner that a good sealing is attained. Special filling pieces 65 12, 25 are welded to the plates 1, 2 at the widened parts of the channels 3 or 4, i. e. adjacent to the slots 11, 19, 20, to make the space for the packing wedge-shaped, decreasing to about the half of the width at said places, as is best seen at 26 in Fig. 3. When mounting said packings, it is, therefore, 70 necessary to press the ends of the packings with force into said spaces and consequently a good sealing is attained and the ends of the packings are securely fixed to the channels.

To prevent any mixing of the liquids in the 75 apparatus the spiral channels 27 formed between

the packings 24 and the side plates 8 are drained by means of vertical slots 28 cut into the lower half of said side plates to permit all liquid possibly leaking out to flow away. To give the passage of flow in the channels 28 a safe size 80 the side plates 8 are not pressed tightly to the edges of the plates 1, 2, distance sleeves 30 being provided on the bolts 29 serving to secure said side plates 8 to the rings to prevent over-tightening of said side plates. 85

The sealing described has the following advantages in comparison, for instance, with that construction, in which the sides of the apparatus are closed by means of plane disks and intermediate plane rubber packings: The apparatus 90 in accordance with the invention is cheaper, because neither the end surface of the plates 1 and 2 nor the side plates 8 need be planed. Such planing is a very expensive procedure and in using stainless iron almost impossible to effect. 95 The thickness of said side plates and the dimensions of the connections 29, 30 may, in accordance with this invention be considerably reduced, because the pressures on the side plates is considerably lower than that occurring in the construction using plane circular packing disks. 100

Furthermore, the sealing strips in accordance with this invention may be removed and again inserted several times without being destroyed, while on the contrary a plane packing can, as a rule, be used only once, because the edges of the plates make deep impressions in the packing as a result of the strong tightening of the side plates necessary when packings of said last-mentioned type are used. 105

It is even possible to omit the side plates 8, if the packings 24 have a sufficiently great width in relation to the radial width of the channels 3 or 4, because in such case the force pressing the packing 24 against the plates 1, 2 is so much stronger than the force tending to press out said packing from the channels 3 or 4 that the packing is securely held in position solely by the friction against the plates 1, 2. 110

To prevent the packings 24 from being pressed 115 out of the channels 3 or 4 during the operation of the apparatus the plates 1, 2 may also be provided with low collars or flanges 31 at their edges along their whole peripheral length, as shown in Fig. 6. Said collars or flanges need only be small 120 and then they hinder neither the removal of the packings nor the cleaning of the channels 3 or 4. If the thickness of the plates 1, 2 is sufficiently great, recesses 32 may be substituted for said flanges at the peripheral edges of the plates, as 125 shown in Fig. 7. In such case the packing is 130 preferably constructed with a U-shaped section to fit snugly in said recesses.

It is evident from the statements above that the tube 9 forms one end of the channel 3 and the tube 17 the other end of the same channel, while the tubes 10 and 18 constitute the two ends of the channel 4. The liquids may be caused to flow in counter-current or in the same direction through the apparatus, as desired. In the embodiment shown only two spiral channels are illustrated, but the apparatus may of course be constructed with more than two parallel spiral channels for heat transmission between two or more liquids simultaneously. 135

Heat-exchangers having spiral heat transmitting surfaces have the double advantage of a great heat transmitting surface and a small volume and simultaneously a great length of the heat transmitting surface in the direction of 140 145 150

flow without sharp changes of the direction of flow within the apparatus. Consequently, such apparatus have high coefficients of heat transmission and a minimum resistance to the flow 5 and require a minimum of pumping work.

By use of the apparatus in accordance with this invention a low total resistance is secured because the channels are nowhere throttled and because the losses at the inlets and outlets are 10 low on account of the successively decreasing or increasing cross-section of the channels at those places. Thus, a uniform acceleration or retardation of the flowing liquids is attained with minimum losses of pressure.

15 In the embodiment shown in Figs. 3 and 8 the tubes 9 and 10 (only tube 9 is shown in Fig. 8) are stayed by means of cam flanges 33 welded to the outer surface of the tube at suitable distances from each other. Said flanges have preferably 20 the shape of circular plates having eccentric holes for the tubes, as shown. The flanges render the stays 21 superfluous, as shown in Fig. 8.

For the two sheets of metal 1, 2 one single metal sheet may be used which is then doubled to form 25 the tube 15 at the centre of the apparatus so that said tube 15 is integral with the walls of the two channels in which the two fluids flow in heat exchanging relation to each other. In this case the single doubled plate becomes in effect 30 two plates.

What we claim is:—

1. In a heat-exchanger, in combination, parallel heat transmitting surfaces of sheet metal bent to a spiral shape, distance pieces inserted 35 between said surfaces adjacent to the edges of the spiral which are at right angles to the axis thereof, said distance pieces having small dimensions in the peripheral and axial direction of said spiral, and removable packings of a resilient material at said edges to close the space between said surfaces.

2. In a heat-exchanger, in combination, two or 40 more metal plates bent to substantially parallel spirals forming channels between themselves, said channels having successively increasing cross-sectional areas at their ends, distance pieces secured between said plates adjacent to their spiral edges, said distance pieces being narrow in the peripheral and the axial directions of said spiral plates, and removable packings of a 45 resilient non-metallic material in the open spaces at the spiral edges of said plates to seal said channels at those surfaces of the spirals, which are substantially at right angles to the axis thereof.

3. In a heat-exchanger, in combination, two or 50 more metal plates bent to substantially parallel spirals forming channels between themselves, distance pieces between said plates and welded to said plates adjacent to their spiral edges, said

55 distance pieces being narrow in the peripheral direction and also in the axial direction of said spiral plates, tubes at the periphery and at the centre of said spiral plates and provided with slots which extend substantially the entire axial width of said spiral plates, liquid-tight connections between said plates and said tubes on both sides of said slots, stays secured across said slots between the edges thereof and removable packings of a resilient material in the open spaces

60 at the spiral edges of said plates to seal said channels at those surfaces of the spirals, which are substantially at right angles to the axis thereof.

4. In a heat-exchanger, in combination, two or 65 more rectangular metal plates bent to sub-

stantially parallel spirals with channels therebetween, distance pieces inserted between and welded to said plates adjacent to their spiral edges, said distance pieces being narrow in the peripheral and axial directions of said spiral plates, tubes at the periphery and at the centre of said spiral plates and slotted to a distance corresponding substantially to the entire axial width of said spiral plates and hermetically connected with said plates on both sides of said slots, stays secured across said slots between the edges thereof, flanges welded on the outside of those of said tubes, which are arranged at the periphery of the spiral plates, and removable packings of a non-metallic material in the open ends of said channels to seal them in the axial direction.

5. In a heat-exchanger, in combination, two or more metal plates bent to substantially parallel spirals forming channels between themselves, distance pieces inserted between and welded to said plates adjacent to their spiral edges, said distance pieces being narrow in the peripheral direction and also in the axial direction of said spiral plates, tubes at the periphery and at the centre of said spiral plates and provided with slots throughout substantially the entire axial width of said spirals, liquid-tight connections between said plates and said tubes on both sides of said slots, stays across said slots between the edges, additional stays between those tubes, which are arranged at the periphery of said plates, and removable packings of a resilient material at the open ends of said channels to seal them in the axial direction.

6. In a heat-exchanger, in combination, two or more metal plates bent to substantially parallel spirals, forming channels between themselves, said channels having successively increasing cross-sectional areas at their ends, distance pieces secured between said plates adjacent to their spiral edges, said distance pieces being narrow in the peripheral and the axial directions of said spiral plates, and sealing strips of a resilient, non-metallic material inserted into the open spiral ends of said channels to close and seal them in the axial direction.

7. In a heat-exchanger, in combination, two or more metal plates bent to substantially parallel spirals, forming channels between themselves, said channels having successively increasing cross-sectional areas at their ends, distance pieces secured between said plates adjacent to their spiral edges, said distance pieces being narrow in the peripheral and the axial directions of said spiral plates, and sealing strips of a non-metallic, resilient material inserted into the open spiral ends of said channels to close and seal them in the axial direction, said strips having a substantially U-shaped cross section.

8. In a heat-exchanger, in combination, two or more metal plates bent to substantially parallel spirals, forming channels between themselves, said channels having successively increasing cross-sectional areas at their ends, distance pieces secured between said plates adjacent to their spiral edges, said distance pieces being narrow in the peripheral and the axial directions of said spiral plates, sealing strips of a resilient, non-metallic material inserted into the open spiral ends of said channels to close and seal them in the axial direction, and shoulders on said plates at their spiral edges to prevent said strips from sliding outwards axially.

9. In a heat-exchanger, in combination, two or more metal plates bent to substantially paral-
